[57] CLAIM

The ornamental design for a combined firearm and
long-range camera, as shown and described.

DESCRIPTION

FIG. 1 is a perspective view of a combined firearm and
long-range camera showing my new design;
FIG. 2 is a front end elevational view thereof;
FIG. 3 is a rear end elevational view thereof;
FIG. 4 is a side elevational view thereof;
FIG. 5 is a side elevational view opposite of that shown
in FIG. 4;
FIG. 6 is a top plan view thereof; and,
FIG. 7 is a bottom view thereof.

FIG.1.

FIG. 2.

FIG. 4.

FIG. 5.

FIG. 3.

FIG. 6.

FIG. 7.
